ARTICLE HANDLING DEVICE

Bert L. Keeney, Princeton, Ky.

Application July 23, 1938, Serial No. 220,980

8 Claims. (Cl. 214—17)

This invention relates to article handling devices and particularly to article handling devices of the type which may be utilized for introducing and withdrawing films and the like to and from a number of developing or other solutions or fluids in order.

The primary objects of this invention are, to provide in such a device a shaft or element formed with a series of connected longitudinal and rotary guide paths or tracks, and automatic means for moving an article carrier or the like along said paths or tracks; to provide automatic means for shutting off the power in such a machine after the films or articles carried thereby have been immersed in each of the successive solutions or fluids for the requisite length of time; and to provide such a device in which the operation is positive and smooth to allow handling of delicate articles without damaging or unduly jarring the same.

In the accompanying drawings:

Figure 1 is a side elevation of a preferred embodiment of my invention;

Figure 2, a top plan view of Figure 1;

Figure 3, an enlarged sectional view on the line 3—3 of Figure 2 looking in the direction of the arrows, and showing in dotted lines one position of the device during operation with the film carrier suspended in the tank, the control switch being omitted;

Figure 4, a sectional view on the line 4—4 of Figure 3 looking in the direction of the arrows; and

Figure 5, a diagram showing the arrangement of the guide slot or path on the shaft or pipe 4.

Referring now in detail to the accompanying drawings, the numeral 1 designates a fluid containing tank provided with a plurality of vertical relatively parallel separating partitions 2 which divide said tank 1 into a number of separate sections 9, the partitions 2 preferably being integral with the tank 1 and said tank 1 and partitions 2 preferably being coated or lined internally with some suitable material such as glass or wax to withstand the action of the various chemical solutions which are commonly used in the development of films. It is to be noted that the distance between each pair of partitions 2 varies with, or is in proportion to, the length of time in which the films or articles are to be immersed in the fluid contained between said partitions in the tank sections 9.

Fixedly mounted over said tank by any suitable means, such as a bracket 3 riveted or otherwise secured to the forward end of said tank

1, and extending lengthwise thereof across said partitions 2, is a hollow externally screw-threaded pipe or shaft 4 formed with a series of longitudinal slots 5 and 6, the respective adjacent ends of said slots 5 and 6 being connected by a series of rotary slots 7 to form a continuous guide slot generally denoted by the numeral 8. The guide slot 8 is clearly shown in Figure 5 of the accompanying drawings.

The longitudinal slots 5 are disposed on the lower side of the pipe or element 4, preferably in alignment with each other, each said slot 5 being in substantial registry with one of said tank sections 9. The length of each said slot 5 varies in direct proportion to the length of time in which the films are to be immersed in the fluid therebeneath in the respective tank sections 9.

The longitudinal slots 6 are disposed on the upper side of said pipe 4 preferably in alignment with each other and registering respectively with the partitions 2.

It is to be noted that the slots or tracks 6 on the upper side of pipe 4 are not necessary or indispensable and may be omitted, and instead the rotary slots 7 may be made to extend helically for an entire revolution around said pipe, instead of half a revolution as shown, to connect the respective adjacent ends of the respective lower longitudinal slots 5. However it is preferred to include slots 6 since obviously the use of such slots 6 makes for a stronger pipe 4 than would such arrangement. The rotary slots 7 are shown in the preferred embodiment of my invention as being helical and would necessarily be so if the longitudinal slots were omitted as above, however in the preferred construction shown wherein the upper longitudinal slots 6 are included as part of guide slot 8, it is immaterial whether the rotary slots 7 are helical as shown or extend circumferentially around pipe or shaft 4.

It is to be preferred that said guide slot 8 should begin and end with a rotary slot 7, as shown, so that in operation the film carrier 11 may be easily positioned from the top or upper side of pipe 4 without immersing it in any of the developing solutions or fluids prior to the start of the actual developing operation, and at the end of the developing operation the carrier 11 may come to rest in an upwardly extending position above tank 1 and out of the developing fluid.

Disposed for axial and rotary movement within the pipe or hollow shaft 4 is a piston or element 10 which is formed with a socket into

which may be removably inserted the end of a film or article carrier or rod 11, said carrier 11 extending through and engaging the sides of guide slot 8. In the preferred embodiment the carrier 11 is retained in the socket by friction, although the socket and carrier may be provided with cooperating screw-threads, or any other suitable means may be provided for mounting carrier 11 on piston 10.

10 The carrier 11 is provided at its outwardly extending portion with suitable means for releasably engaging and holding a plurality of films or other small articles, said means in the present instance consisting of a plurality of spring clips *a*.

15 Also, suitable means are provided for urging the film carrier 11 through longitudinal slots or tracks 5 and 6 to the respective forward ends thereof, the preferred means consisting of a tension spring 12 attached at one end to a plug 13 fixedly mounted in the forward end of pipe 4, the other end of said spring 12 being attached to piston 10 to pull said piston towards said plug.

20 In order to allow piston 10 to be reset after operation, means preferably consisting of a wire or string 34 and extending rearwardly out of sleeve 15 are provided so that said string 34 may be easily grasped and pulled rearwardly by the operator to move said piston 10 rearwardly back to starting position against the action of spring 12.

25 Mounted concentrically for rotation and axial movement on pipe 4 and having an internally screw-threaded portion 14 in releasable engagement with the threads thereof is a sleeve or carriage 15. The sleeve 15 is supported or rotatably journalled in a bearing or journal 16 integral with a rigid metal plate 33 which in turn is riveted or otherwise suitably attached to the rear end of tank 1 for purposes hereinafter set forth.

30 The screw-threaded portion 14 above referred to preferably consists of a two part internally screw-threaded hinged clamp, permanently attached by means of a permanent pivot pin 17, shown in Figure 4, to the forward end of said sleeve 15. Portion 14 may be locked in position about pipe 4 by means of a removable forwardly projecting actuating pin or lug 18 extending through the interlocked ends of the parts of said clamp 14 to be frictionally or otherwise suitably retained in a socket formed in the adjacent forward end of sleeve 15.

35 The forwardly projecting portion of actuating pin or projection or lug 18 in operation rotates with said sleeve and moves forward slightly in advance of the portion 14 thereof to at the proper time engage and rotate the carrier 11 through said rotary slots 7.

40 In the preferred embodiment of the invention the sleeve 15 is provided adjacent its forward end with a pair of spaced annular shoulders or stops 19 between which is rotatably mounted a ring 20 which carries a forwardly projecting substantially U-shaped yoke 21 extending about carrier 11 to 45 rotate therewith and allow relative longitudinal movement of said carrier 11 in said yoke 21 and at the same time limit the amount of immediate forward or longitudinal movement of said carrier 11 upon its entrance into the longitudinal slots 5 and 6. Yoke 21 by thus checking the forward movement of carrier 11 in said slots 5 and 6 serves to prevent the shock and undue jarring which might occur if the carrier were allowed to be pulled forward at full speed by the action of

5 spring 12 until it reached the ends of said respective longitudinal slots 5 and 6.

However, while the yoke 21 is desirable, it may be entirely omitted without causing undue adverse influence on the operation of the invention.

10 Suitable means are provided for rotating sleeve 15 at a constant rate of rotation to produce a constant rate of relative axial movement between said sleeve or carriage 15 and said pipe 4. The preferred means shown in the accompanying drawings consists of an electrically driven motor 22 mounted on a supporting bracket 23 by suitable means such as bolts 24, the bracket 23 in turn being mounted immovably on plate 33 at the rear end of tank 1 by rivets 25 or other suitable means.

15 Motor 22 in operation transmits rotary motion through a series of speed reduction gears 26 also carried by plate 33, to rotate drive gear 27 mounted for relative axial movement on the rearwardly extending portion of sleeve 15 at the rear of bearing 16. Drive gear 27 is formed with a radially inwardly projecting key or lug 28 disposed for axial movement in a longitudinally extending slot 29 formed in the rearwardly extending portion of sleeve 15 to permit relative axial or longitudinal movement of said drive gear 27 and sleeve 15 and allow said sleeve 15 to be positively engaged and rotated by said drive gear 27.

20 The control means for electric motor 22 preferably consist of a medially pivoted switch lever 30 of electrical conducting material mounted on and suitably insulated from the bracket 3 at the forward end of tank 1, the end of said lever 30 projecting rearwardly into the path of movement 25 of carrier 11, and the forward end of lever 30 being adapted to engage a contact 31, similarly mounted on and insulated from bracket 3, to close the electric motor circuit through wire 32 and supply electricity to motor 22. Motor 22 is 30 preferably grounded on bracket 23 to complete the electric circuit therethrough.

25 To operate the device the sleeve 15 is placed in the position shown in Figures 1, 2 and 3 of the drawings with the screw-threaded portion 14 thereof in engagement with the rearmost part of the screw-threaded portion of pipe 4, after which the piston 10 is pulled rearwardly by means of string 34 to starting position with its socket in registry with the beginning of the rearmost rotary slot 7. After thus placing sleeve 15 and piston 10 in proper starting position the films which are to be developed are disposed in the spring clips *a* of carrier 11 after which the lower end of carrier 11 is passed through yoke 21 and the beginning of rearmost slot 7 to be received and retained during operation in the socket formed in piston 10. In each of Figures 1, 2 and 3 the device is thus shown arranged in proper starting position.

30 After thus positioning the device for starting, the switch lever 30 is pivoted into engagement with contact 31 to close the circuit through motor 22, whereupon sleeve 15 is rotated at a constant relatively slow rate of speed until the pin 18 35 carried thereby engages carrier 11 and rotates it through rotary slot 7 to immerse it and the films carried thereon (not shown) in the fluid or film developing solution contained in the first of said tank sections 9. After being thus immersed, carrier 11 enters into the first of the downwardly disposed longitudinal slots 5, whereupon spring 12 40 serves to immediately pull said carrier 11 to the forward end of yoke 21 out of engagement with pin 18, it being noted that yoke 21 extends for- 45

ward substantially further than does pin 18 to allow sufficient clearance. The carrier 11 and sleeve 15 then move forward together at a constant rate of speed until the carrier reaches the forward end of longitudinal slot 5, whereupon it comes to a stop and remains stationary with the film carrier suspended in tank section 9 adjacent the first of said partitions 2 until sleeve 15 advances far enough for pin 18 carried thereon to again engage and rotate carrier 11 upwardly out of the first tank section 9 through rotary slot 7. After thus emerging from the tank section 9 carrier 11 enters into the upwardly disposed longitudinal slot 6 whereupon it is immediately pulled forward in yoke 21 out of engagement with pin 18 while it moves longitudinally across the top of the first partition 2 until it comes to rest at the forward end of said slot 6 until again engaged by pin 18 for immersion in the next tank section 9, whereupon the foregoing process is repeated, the carrier 11 being repeatedly immersed in each tank section 9 in order and lifted over the respective partitions 2 until it reaches the end of its travel in guide slot 8. At the end of its path of movement, when rotating upwardly through the last rotary slot 1, carrier 11 engages the rearwardly extending switch lever 30 and rotates the same away from contact 31 to shut off the supply of electricity to motor 22. The developed films may then, if desired, be left in clips *a* to dry.

The dotted lines in Figure 3 show the relative positions of carrier 11, yoke 21 and sleeve 15 during the longitudinal movement of carrier 11 through one of the longitudinal lower slots 5.

In order to repeat the above process, the developed films are first removed from clips *a* and carrier 11 is removed from its socket in piston 10, after which pin 18 is removed allowing the two parts of clamp or portion 14 to be spread apart and disengaged from about pipe 4 so that sleeve 15 may then be freely moved axially back to starting position. The piston 10 is then placed in starting position as hereinbefore described to receive carrier 11 having a new batch of films mounted thereon for development or treatment.

Although the preferred form of the invention herein shown and described has been adapted for use as an automatic film developer it might equally well be adapted for use in automatically dipping and removing small articles from a plating solution or staining microscope slides and similar uses, without departing from the scope of the invention.

I claim:

1. An automatic film developer comprising, a hollow externally screw-threaded pipe formed with a series of longitudinal slots having their respective adjacent ends connected by a series of rotary slots to form a continuous guide slot; a piston disposed for axial and rotary movement within said pipe and formed with a socket; a film carrier removably frictionally mounted in said socket and extending through and engaging the sides of said guide slot; and means for urging said carrier through said longitudinal slots comprising a plug disposed in the forward end of said pipe and a tension spring disposed in said pipe with its ends respectively attached to said plug and said piston; in combination with a sleeve mounted concentrically on said pipe and having an internally screw-threaded portion in removable engagement with the threads thereof; means for rotating said sleeve at a constant rate of speed to produce a constant rate of relative axial movement between said sleeve and said

pipe; a U-shaped yoke rotatably mounted on said sleeve to receive said carrier and limit the rate of longitudinal movement thereof in said longitudinal slots, said carrier in its travel through said longitudinal slots being urged to the respective forward ends thereof by said tension spring; a forwardly extending pin mounted on said sleeve to engage said carrier at the end of its path of movement through each of said longitudinal slots and rotate the same through said respective rotary slots, said pin extending forwardly substantially less than said yoke so as not to engage said carrier during its travel through said longitudinal slots; and automatic control means for rendering said sleeve rotating means inoperative when said carrier reaches the extreme forward end of said guide slot.

2. An automatic film developer comprising, a hollow externally screw-threaded pipe formed with a series of longitudinal slots having their respective adjacent ends connected by a series of rotary slots to form a continuous guide slot, a piston disposed for axial and rotary movement within said pipe and formed with a socket, a film carrier removably frictionally mounted in said socket and extending through and engaging the sides of said guide slot, and means for urging said carrier to the respective forward ends of said longitudinal slots comprising a plug disposed in the forward end of said pipe and a tension spring disposed in said pipe with its ends respectively attached to said plug and said piston, in combination with a sleeve mounted concentrically on said pipe and having an internally screw-threaded portion in removable engagement with the threads thereof, means for rotating said sleeve at a constant rate of speed to produce a constant rate of relative axial movement between said sleeve and said pipe, and a forwardly extending pin mounted on said sleeve to rotate therewith and engage said carrier at the forward end of each said longitudinal slot to rotate the same through each said rotary slot, said longitudinal slots being of substantially greater length than said pin and the rate of forward movement of said carrier in said longitudinal slots being substantially greater than the rate of forward movement of said pin, so that said pin will engage said carrier only after it reaches the end of each said longitudinal slot.

3. An automatic film developer comprising, a hollow externally screw-threaded pipe formed with a series of longitudinal slots having their respective adjacent ends connected by a series of rotary slots to form a continuous guide slot, a piston disposed for axial and rotary movement within said pipe, a film carrier removably mounted on said piston and extending through and engaging the sides of said guide slot, and means for urging said carrier to the respective forward ends of said longitudinal slots, in combination with a sleeve mounted concentrically on said pipe and having an internally screw-threaded portion in removable engagement with the threads thereof, means for rotating said sleeve at a constant rate of speed to produce a constant rate of relative axial movement between said sleeve and said pipe, and a forwardly extending pin mounted on said sleeve to rotate therewith and engage said carrier at the forward end of each said longitudinal slot to rotate the same through each said rotary slot, said longitudinal slots being of substantially greater length than said pin and the rate of forward movement of said carrier in said longitudinal slots being substantially greater than the

rate of forward movement of said pin so that said pin will engage said carrier only after said carrier reaches the end of each said longitudinal slot.

- 5 4. An automatic film developer comprising, a hollow externally screw-threaded pipe formed with a series of longitudinal slots having their respective adjacent ends connected by a series of rotary slots to form a continuous guide slot, 10 a piston disposed for axial and rotary movement within said pipe, a film carrier removably mounted on said piston and extending through and engaging the sides of said guide slot, and means for urging said carrier to the respective forward 15 ends of said longitudinal slots, in combination with a sleeve mounted concentrically on said pipe and having an internally screw-threaded portion in removable engagement with the threads thereof, means for rotating said sleeve at a constant rate of speed to produce a constant 20 rate of relative axial movement between said sleeve and said pipe, and a forwardly extending pin mounted on said sleeve to rotate therewith and engage said carrier at the forward end of each said longitudinal slot to rotate the same through said rotary slots.
- 30 5. An article handling device comprising, a hollow externally screw-threaded pipe formed with a series of longitudinal slots having their respective adjacent ends connected by a series of rotary slots to form a continuous guide slot, 35 a piston disposed for movement within said pipe, a film carrier mounted on said piston and extending through and engaging the sides of said guide slot, and means for urging said carrier to the respective forward ends of said longitudinal slots, in combination with a sleeve mounted concentrically on said pipe and having an internally

screw-threaded portion in engagement with the threads thereof, means for rotating said sleeve, and means mounted on said sleeve to rotate therewith and engage said carrier at the forward end of each said longitudinal slot to rotate the same through said rotary slots. 5

6. An article handling device comprising, a shaft formed with a series of longitudinal and rotary slots connected to form a continuous guide slot, an article carrier mounted for movement in 10 said guide slot, and means for moving said carrier through said longitudinal slots, in combination with a sleeve mounted concentrically on said shaft, means for simultaneously rotating and axially moving said sleeve, and means carried by 15 said sleeve to engage said carrier and rotate the same through said rotary slots.

7. Article handling means comprising a shaft formed with a series of connected longitudinal and rotary guide slots, an article carrier mounted 20 for movement through said guide slots, and means for moving said article carrier through said longitudinal slots, in combination with means mounted for relative axial and rotary movement about said shaft to engage said carrier and move the same through said rotary slots. 25

8. Article handling means comprising a shaft formed with a series of connected longitudinal and rotary guide tracks, an article carrier mounted for movement along said tracks, and means for 30 moving said article carrier along said longitudinal tracks, in combination with means normally unengaged for engaging said carrier at the beginning of each said rotary track to rotate it therethrough and thereafter release it for movement along one of said longitudinal tracks. 35

BERT L. KEENEY.
